R. Birkhards

Inventor:
John A. Lamont,
By Wilkins, Shadley, Brown & Knight
Atty.

UNITED STATES PATENT OFFICE.

JOHN A. LAMONT, OF CHICAGO, ILLINOIS, ASSIGNOR TO AMERICAN STEEL FOUNDRIES,
OF CHICAGO, ILLINOIS, A CORPORATION OF NEW JERSEY.

RAILWAY-CAR-TRUCK CONSTRUCTION.

Application filed July 18, 1921. Serial No. 485,431.

To all whom it may concern:

Be it known that I, JOHN A. LAMONT, a citizen of the United States, residing at Chicago, in the county of Cook and State of Illinois, have invented certain new and useful Improvements in a Railway-Car-Truck Construction, of which the following is a specification.

This invention relates to railway car truck constructions and more particularly to the cooperative association between a journal box, side frame and some of the equalizing parts associated therewith.

One object of the invention is to provide a truck side frame, journal box and equalizing mechanism which cooperate with each other in a manner to improve the operative efficiency of the truck.

Another object of the invention is to provide a combination of parts in a six-wheel car truck adapted to meet the various requirements of service conditions.

These and other objects are accomplished by means of the arrangement disclosed on the accompanying sheet of drawings, in which—

Figure 1 is a fragmentary side elevation, parts being in section, of a six-wheel truck embodying my invention; and

Figure 2 is a sectional view taken in the plane of line 2—2 of Figure 1.

The various novel features of the invention will be apparent from the following description and drawings and will be particularly pointed out in the appended claims.

Referring to the figures of the drawings it will be noted that I have disclosed my invention in connection with a six-wheel equalizing truck including a side frame 10 having a central journal box opening 11 for the reception of the journal receiving portion 12 of an intermediate journal box 13. This journal box is provided with laterally extending brackets 14, the upper surfaces of which are located considerably below the center line of the journal 15 for a reason to be explained later. Mounted upon the brackets 14 are coiled springs 16 which are bridged by a cap 17 which carries in groove 18 at the middle thereof a pivot pin 19 upon which an equalizing beam 20 is pivotally mounted. The outer ends of this equalizing beam 20 are directly engaged by inner end portions 21 of associated equalizing levers 22 which transmit loads from bolster mem-

bers through the equalizing beam 20, spring cap 17 and springs 16 to the journal box 13.

It will be noted that the loads are transmitted to the journal box 13 at a point below the center line of the journal 15 whereby any tendency for the journal box to tip one way or the other is reduced. This also reduces the amount of wear which otherwise would occur between the journal box and its guides and on journal brasses. In this connection it will be noted that the journal receiving portion 12 of the journal box 13 is embraced by a steel wearing band 23 which cooperates with the side frame walls 24 formed integrally with the side frame. 70 These walls 24 also embrace or enclose a substantial part of the coiled spring 16. Not only are the walls 24 formed integrally with the side frame, but also walls or shoulder portions 25 are formed integrally with the side frames and these portions 24 and 25 act as guides for the relative vertical movement of the side frame and the spring cap 17, said spring cap having downwardly extending portions 26 and upwardly extending portions 27 which cooperate with said guide portions 24 and 25. There is relative movement between the spring cap 17 and the side frame when the truck is moved over uneven tracks or on a switch-back. Let it be assumed that the middle pair of wheels is caused to drop lower than the two outer pair of wheels. In such case the intermediate journal boxes 13 lower and the springs 16, spring cap 17, equalizing beam 20 and inner ends 80 of the equalizing levers 22 follow, the side frame remaining stationary. Conversely, when the middle pair of wheels is caused to rise above the two outer pair of wheels the intermediate journal boxes 13 are caused to rise and with them the springs 16, spring cap 17, equalizing beam 20 and inner ends 90 of equalizing levers 22. During these relative movements the spring cap is guided by the guide portions 24 and 25 and the journal 100 box is guided by the wall or guide portions 24.

Referring particularly to Figure 2 of the drawings, it will be noted that the equalizing beam 20 is mounted between the side walls 28 of the spring cap 17 and that the spring cap in turn is mounted between the side walls 29 of the side frame at the section shown. Also the side walls 29 of the side frame are embraced by upwardly ex- 110

tending walls 30 formed integrally with the journal box 13 whereby all of the parts mentioned are maintained in proper, relative lateral position.

5 It is my intention to cover all modifications of the invention falling within the spirit and scope of the following claims.

I claim:

1. In a six-wheel truck, the combination 10 of a side frame having an opening formed by walls for the reception of a journal box, a journal box mounted in said opening and guided in its relative movements with respect to said side frame by said walls, 15 springs carried by said journal box, and a spring cap bridging said springs and being guided in its relative movements with respect to said side frame by said same guide walls.
- 20 2. In a six-wheel truck, the combination of a side frame having an opening formed by walls for the reception of a journal box, a journal box mounted in said opening and guided in its relative vertical movements 25 with respect to said side frame by said walls, springs carried by said journal box, and a spring cap bridging said springs and being guided in its relative vertical movements with respect to said side frame by said same

guide walls, there being other guide portions 30 on said side frame for cooperating with portions of said spring cap for cooperating in guiding the latter in its relative movements with respect to said side frame.

3. In a railway car truck, the combination 35 of a side frame having a walled opening in which a journal box may guidedly move in a vertical direction, resilient means carried by said journal box, and equalizing means including a cap mounted over said resilient 40 means guided in its vertical movements with respect to said side frame by the walls around said opening.

4. In a railway car truck, the combination 45 of a side frame having a walled opening in which a journal box may guidedly move in a vertical direction, resilient means carried by said journal box, equalizing means including a cap mounted over said resilient 50 means guided in its vertical movements with respect to said side frame by the walls around said opening, and other guide means formed integrally with said side frame for cooperating to guide said cap in its relative movements with respect to said side frame. 55

Signed at Chicago, Illinois, this 6th day of July, 1921.

JOHN A. LAMONT.
